J. G. WALLMANN.

COMBINED LIQUID FUEL CONTROL FOR MOTOR CARS AND GRADE METERS.
APPLICATION FILED DEC. 3, 1913.

1,120,772.

Patented Dec. 15, 1914.

Fig. 4.

WITNESSES:

F. C. Fliedner
Chas. P. Sonntag

A vertical thermometer scale with markings from 20 to 30. The scale is labeled with 16, 34, and 30.

A vertical cross-section of a pipe assembly. On the left, a vertical column of numbers identifies parts: 16 at the top, followed by 30, 31, 32, 33, and 34. On the right, the letters 'Fi' are written above a curved pipe segment. The bottom right corner of the diagram is labeled with the number 17, and just below it is the number 18.

JOHANN G. WALLMANN, OF OAKLAND, CALIFORNIA.

COMBINED LIQUID-FUEL CONTROL FOR MOTOR-CARS AND GRADE-METERS.

1,120,772.

Specification of Letters Patent. Patented Dec. 15, 1914.

Application filed December 3, 1913. Serial No. 804,436.

To all whom it may concern:

Be it known that I, JOHANN G. WALLMANN, a citizen of the United States, residing at Oakland, in the county of Alameda and State of California, have invented certain new and useful Improvements in Combined Liquid-Fuel Controls for Motor-Cars and Grade-Meters, of which the following is a specification.

10 My invention relates to improvements in combined liquid-fuel controls for motor-cars and grade-meters.

The object of my invention is to provide a device for motor-cars which is particularly 15 designed to effect saving in liquid-fuel as used therein, and also to give the engine therein greater power and speed, less carbon, and a lower temperature, while permitting the use of a heavier gasoline than is 20 usually used in the operation of such cars. Said device is also designed to relieve to a great extent the wear and tear on the brakes while used on hills. It automatically adjusts the proper mixture of fuel when as- 25 cending or descending grades, while on steep grades in the descent it automatically adjusts itself so as to allow a large amount of air to enter the cylinders by way of the manifold used, and the operator can allow the car to 30 descend a hill on compression, saving wear on the brakes and effecting a cooling of the engine. The mixture can be made tempo- 35 rarily rich on stopping as a means for "start- 40 ing on the spark." The mixture can be cor- 45 rected for altitude while the operator is seated at the wheel without touching the carbureter. The device will give the operator the pitch of the grade while ascending or descending the same, and he can also 50 ascertain the nature of the grade the car can climb without changing gears. As the adjustment of the carbureter is good only for the time it is made, the slightest change in the weather, temperature, altitude, or in the 55 grade of gasoline, will result in the mixture becoming too weak or too rich; this disadvantage is overcome in my device, and the proper way to regulate the air supply is while the car is traveling, and by the use of 60 said instrument the mixture can be instantly changed.

My invention consists in the combination and arrangement of parts shown in the accompanying drawing, described in the fol-

lowing specification and claimed in the ap- 55 pended claims.

Referring to the accompanying drawings: Figure 1 is a side elevation of my apparatus; Fig. 2 is a section on the line B—B of Fig. 1; Fig. 3 is a plan view of the air-regu- 60 lating chamber detached; Fig. 4 is a front view of the grade-meter; Fig. 5 is a sectional view of said grade-meter.

In said figures 1 represents a hand ad- 65 justing-wheel secured to the adjusting rod 2, and which rod is mounted in a bearing therefor secured to the motor-car as shown. An arm 3 is engaged by the threads of said rod and constitutes part of the movable valve-piece or internal casing having open- 70 ing 25. A wire screen 4 is mounted in the branch of movable valve-piece or external casing 6. An arm 7 is screwed to external casing 6 and is linked to piston 15 of dash pot 14, which is pivoted to frame 37, the said 75 frame being screwed to part of the car as shown. A rod 9 is secured in the lower side of casing 6 and penetrates weight 10 sus- 80 pended thereby. The said rod 9 has a collar 12 supporting a spring 11 engaging and up- 85 holding said weight 10. An elbow 36 is secured to an extension of casing 26 and has a branch or nipple 8 for hose 20 secured to the nipple by ring or clamp 21. Said hose is also secured to manifold 49 by means of 90 piece or nipple 47. A similar ring or clamp 21 secures said hose to nipple 47.

A grade-meter 16 has a guide tube 17 con- 95 taining wire 18 connected to rod 9 by screw 22. The said grade-meter contains glass 30 90 and indicator-needle 34 for registration. An indicator card in said meter is designated 31 and said meter has a back preferably of metal 32. The said meter has also an indi- 95 cator-guide 33. A valve-chamber 35 is con- tained in said casing 26.

Guide brackets 19 have holes 24 for lock screws and are secured to fiber insulation 46 as shown. Wires 40 and 41 are intended to cut out spark coils. Binding screws 42 and 100 45 secure said wires 40 and 41 as shown. Spring contacts are shown at 43 and 44.

The device is secured to the dash board of a motor-car as shown in Fig. 1. It is then connected to the manifold by means of the 105 rubber hose 20 and the pipe nipple 47. By turning the thumb screw 1 clockwise the threads of part 2 cause arm 3 to be carried

- slowly forward, causing the valve part 26 to revolve in casing 6. This forward movement of casing 26 causes port 25 to open and the farther the movement of said part 26 5 advances the larger the port resulting. In the way set forth, air may be allowed to enter the manifold 49. By turning the thumb-screw counter clockwise the port may be closed. The car is now ready to start with 10 the device in the last mentioned position. As no air can now enter the manifold by means of the instrument such position allows a rich mixture of liquid fuel for starting. As the carbureter adjustment is good only 15 for the time it is made, the slightest change in weather, temperature, altitude or gasoline occurring will cause the mixture used to become too thin or too rich. For these reasons the operator will adjust the carbureter to 20 produce the mixture slightly rich. Having started the engine, the proper way to regulate the mixture is while the car is running on a level road, when by turning the thumb-screw clockwise the port 25 may be opened. 25 The operator can ascertain by the running of the engine when he has or is allowing the proper amount of air for the proper mixture for running. Thus the car can be adjusted for smooth and economical running on level 30 roads. The air is drawn in through the fine screen 4 into valve chamber 35; then through the elbow 36; through hose connection 8; through hose 20, then through the nipple 47 into the manifold 49. The car 35 being adjusted for level roads, on climbing a hill the air is automatically shut off, as it is necessary to have a rich mixture for smooth and steady running of the car in climbing hills. 40 The automatic device operates in the following way: On ascending a hill, the pendulum will move in a direction as may be marked "Up hill," that is the steeper the hill to be climbed, the farther it will recede, 45 the same always remaining in a perpendicular position. As the pendulum moves in said direction, the valve piece 6 turns, closing the port 25 or partly closing it, the degree of closing depending on the steepness 50 of the grade. The closing of said port and the cutting off of the compensating air, will cause the engine to draw a richer mixture as is necessary for smooth and easy running of the car on grades. When the car reaches 55 level ground again the pendulum automatically turns the valve-piece 6 so that the port 25 is again in its original adjustment. The machine on descending a grade causes the pendulum to move in a direction as may be 60 marked "Down hill," this movement causing the port to open; and on a steep grade, the large volume of air entering through the valve into the manifold relieves the suction on the carbureter, thereby drawing in 65 pure air as the machine is running down hill and using the engine's own compression as a brake. The forward movement of the pendulum causes the weight 10 to come in contact with the spring contact 48, forcing it out of contact with part 44, thus opening 70 the magneto or battery circuit to the spark plugs. The bumper 48 is insulated. The part 14 is attached to the valve-piece 6 by the arm 7, this dash pot keeping the pendulum from swinging; which may be caused 75 by a jar in the car, caused by it coming in contact with a rut in running. Spring 11 takes off all the jar upwardly or downwardly from the weight on the rod 9. The small steel wire 18 connects with the indicator 80 finger 34, on the grade-meter, 16. In the two holes 24 of the combination brackets and guide arms 19 may be set screws to lock the pendulum.
- I claim:—
1. In a motor-car in combination with a manifold, a turnable shaft, an internal casing having an opening and an arm movably engaging said shaft, an external casing loosely inclosing said internal casing, a pendulum suspended from the base of said external casing, an elbow having a nipple secured to one end of said internal casing, said casing opening into said elbow, a hose connected to said nipple and leading to said manifold, a movable arm connected to one end of said external casing, a dash pot, with piston joined to said movable arm and penetrating said dash pot and adapted to work therein, and a fixed frame in pivotal connection with the lower end of said dash pot. 90
  2. In a motor-car in combination with a manifold, a turnable shaft, an internal casing having an opening and an arm movably engaging said shaft, an external casing loosely inclosing said internal casing and having an open lateral branch, a pendulum suspended from the base of said external casing, means opening from said external casing to said manifold and connecting said casing with said manifold for the transmission of substance between said parts, a movable arm connected to one end of said external casing, a dash pot, with piston joined to said movable arm and penetrating said dash pot and adapted to work therein, and a fixed frame in pivotal connection with the lower end of said dash pot. 100
  3. In a motor-car in combination with a manifold, a turnable shaft, an internal casing having an opening and an arm movably engaging the said shaft, an external casing loosely inclosing said internal casing and having an open lateral branch provided with a screen, a pendulum suspended from the base of said external casing, means connecting said external casing with said manifold for the transmission of substance between said parts, a movable arm connected to one end of said external casing, a dash 110
  - 120
  - 125
  - 130

- pot, with a piston joined to said movable arm and penetrating said dash pot and adapted to work therein, and a fixed frame in pivotal connection with the lower end of said dash pot.
4. In a motor-car, a turnable shaft, an internal casing having openings and an arm movably engaging the said shaft, an external casing having a side opening and loosely inclosing said internal casing, a pendulum suspended from the base of said external casing a movable arm connected to one end of said external casing, a dash pot having a piston connected to said movable arm, a fixed frame in pivotal connection with the lower end of said dash pot, and means for transmitting fluid from said internal casing.
5. In a motor-car, a turnable shaft, an internal casing having openings and an arm movably engaging the said shaft, an external casing having a side opening and loosely inclosing said internal casing, a pendulum suspended from the base of said external casing, a movable arm connected to one end of said external casing, a dash pot having a piston connected to said movable arm, a fixed frame in pivotal connection with the lower end of said dash pot, means for transmitting fluid from said internal casing, fiber insulation guide brackets endwise connected to said fiber insulation, spring contacts secured to sides of said fiber insulation, current-conducting means in connection with said spring contacts, a grade-meter including a longitudinally-movable guide and needle, and means connecting said grade-meter with the rod of said pendulum.
6. In a motor-car in combination with a manifold, a turnable shaft, an internal casing having a side opening and an end opening, an external casing having a branch provided with a screen and loosely containing said internal casing, a pendulum suspended from the base of said external casing and provided with a longitudinally movable weight supported by a spring, an elbow having a nipple secured to one end of said internal casing, said casing opening into said elbow, a hose connected to said nipple and leading to said manifold, a movable arm connected to one end of said external casing, a dash pot having a piston connected to said movable arm, a fixed frame in pivotal connection with the lower end of said dash pot, a grade-meter having a longitudinally-movable guide and needle, means connecting said grade-meter with the rod of said pendulum, fiber insulation, guide brackets intermediately provided with holes and endwise connected to said fiber insulation, a bent spring-contact secured to one side of said fiber insulation, a spring-contact having a bent end endwise and movably connected to the other side of said fiber insulation, current-conducting means in connection with said spring-contacts, and an arm extending from said internal casing and engaging said turnable shaft.

In testimony whereof I affix my signature in presence of two witnesses.

JOHANN G. WALLMANN.
